UNITED STATES PATENT OFFICE.

JACOB SÜNDER AND EBERHARDT RENNO, OF OBERURSEL, GERMANY, ASSIGNEES TO
FIRM OF ADRIAN & BUSCH, OF OBERURSEL, GERMANY.

SHOE-SEWING MACHINE.

Original application filed December 21, 1923, Serial No. 682,088, and in Germany December 28, 1922.
Divided and this application filed February 11, 1925. Serial No. 8,545.

This invention relates to improvements in sewing machine take-ups, and more particularly to that class of take-ups in which a take-up lever is fulcrumed on a fixed shaft and is connected at one end by means of links to a rotary actuating crank. The invention has for its object to impart to the free end of the take-up such an oscillatory movement as to move slowly upwards and to deliver uniformly the thread while the loop is formed and to move thereafter rapidly down to take care of the surplus of the thread. This object of the invention is attained by means of the novel features of construction and combination of parts, as hereinafter set forth in detail, the present application being a division of application No. 682,088, filed December 21, 1923.

In the drawings Figs. 1-4 illustrate the different positions of the take-up and the co-operating parts of a sole sewing machine embodying the present invention, Figs. 1-8 show the moving mechanism of the take-up in different positions. Fig. 9 is a diagram of the take-up mechanism.

Figs. 1 to 4 illustrate the succeeding working positions of the take-up 34 and the co-operating sewing instruments of a sole sewing machine. In the position shown in Fig. 1 the needle has pierced the work and catches the thread; the take-up lever 34 has reached the end of its downward stroke. The thread finger 31 pulls the thread rearward and the looper manipulates the thread into the barb of the needle 18. The needle begins to return and to draw the loop through the work. In the wholly retracted position of the needle the loop spreader 20 opens the loop (see Fig. 2) to be taken by the rotating hook 21. To ensure the operation of the revolving hook, the needle 18 advances a little and frees the loop from the barb, see Fig. 3. Finally the needle returns to its most retracted position, see Fig. 4. By the rotation of the hook 21 the loop is passed round the bobbin case 36 until it reaches the highest point of the case whereupon the loop slips down from the case. While the thread is caught by the needle and the loop is formed and passed around the bobbin case the take-up lever must slowly and uniformly deliver the thread. On the contrary the loop gliding down from the bobbin case must be taken care of by a rapid movement of the take-up lever. These movements

of the take-up lever are obtained by the following arrangement.

The take-up 34 is formed by a two-armed lever revolvably mounted on the fixed shaft XXIX of the machine frame and connected at XXVIII to the toggle lever 37. On the rotating shaft 2 of the machine is fastened the eccentric 38 carrying the strap 39 with the eccentric-rod 40. The latter is connected at its upper end by the pivot XXIII to the lever 41 swinging upon the shaft XXIV. The strap 39 has a further prolongation or eye 42 to accommodate the pivot XXV for the toggle-lever 43. The toggle-levers 37, 43 are connected to each other and to the swinging lever 44 by the pivot XXVI, the swinging lever 44 itself being rotatably mounted on the shaft XXVII.

The eccentric turns in the direction indicated by the arrow and assumes successively the positions shown in Figs. 5 to 8. From an inspection of the drawings it will be apparent that the upward movement of the take-up lever from the position shown in Fig. 5 to the position in Fig. 8 corresponds to an angle of rotation much greater than the angle corresponding to the downward movement of the take-up lever. The upward movement and the downward movement of the take-up lever are of the same extent, but they are performed with different velocities. The upward movement corresponds to nearly $\frac{3}{4}$ of the revolution of the eccentric and the downward movement corresponds to the remaining $\frac{1}{4}$ of the revolution. The upward movement is therefore a comparatively slow one and serves for the delivery of the thread while the comparatively rapid downward movement serves for the stitch setting.

The parts 38, 40, 41 form three sides of a driving four side linkage, the machine frame between the shafts 2 and XXIV representing the fourth unmovable side of the linkage, see diagram of Fig. 9. The eccentric 38 of Figs. 5-8 is equivalent to the crank 38 of Fig. 9, connected by the rod 40 to the pivot XXIII of the swinging lever 41. The four pivots of the linkage are XXI, XXII, XXIII and XXIV and the linkage itself may be denominated as four side rotating linkage. The connecting rod 40 has the prolongation 42 beyond the pivot XXII (equivalent to the strap 39) to the pivot XXV. On the other hand the parts 44, 37 and the upper arm of

the lever 34 form a second four side linkage with the pivots XXVII, XXVI, XXVIII, and XXIX. But this linkage comprises no revolving parts and may therefore be denominated as an oscillating linkage. Both linkages are connected to each other by the link 43.

During the rotation of the eccentric or the crank 38 the pivot XXII describes the arc xy and the pivots XXV, XXVI describe the corresponding paths $x'y'$ and $x''y''$ respectively which are nearly rectangular to each other. In view of the fact that the path $z''z''$ represents the whole oscillation of the pivot XXVI it will be apparent that the swinging lever 44 will move rapidly upwards along the path $x''y''$ while the crank-pivot XXII describes the arc xy and that it will move

along this path slowly downward while the crank 38 describes the rest of the circle. 20 Movements of small extent on the line $x'y'$ cause movements of great extent on the line $x''y''$.

What we claim is:

In a shoe sewing machine, a rotating eccentric, a swinging lever, a strap coacting with the eccentric and connected to the swinging lever, a swinging take-up lever, and a connection between the strap of the rotating eccentric and to the take-up lever respectively and hinged to each other at their inner ends for the purpose specified. 25 30

In testimony whereof we affix our signatures.

JAKOB SÜNDER.

EBERHARDT RENNO.
